UNITED STATES PATENT OFFICE.

JAMES E. COLLINS, OF BEVERLY, MASSACHUSETTS, ASSIGNOR TO UNITED SHOE MACHINERY COMPANY, OF PATERSON, NEW JERSEY, A CORPORATION OF NEW JERSEY.

CUTTING-MACHINE.

1,083,349.

Specification of Letters Patent.

Patented Jan. 6, 1914.

Application filed February 3, 1913. Serial No. 746,031.

To all whom it may concern:

Be it known that I, JAMES E. COLLINS, a citizen of the United States, residing at Beverly, in the county of Essex and State 5 of Massachusetts, have invented certain Improvements in Cutting-Machines, of which the following description, in connection with the accompanying drawings, is a specification, like reference characters on the drawings indicating like parts in the several figures.

This invention relates to machines a distinctive feature of which is a member that is movable intermittently at the will of the 15 operator to impart pressure or deliver a blow to an object, and commonly comprising relatively movable members arranged to operate upon an object therebetween.

In its more limited application, my invention relates to a particular type of machine commercially known as the clicking machine, of which an example is shown in United States Letters Patent to Arthur Bates, No. 921,503, granted May 11, 1909. 20 Such machines, as usually constructed, include a stock supporting bed, and a presser member that is movable over the bed to an operative position with respect to a die on the bed and subsequently movable automatically at the will of the operator to force the die through the stock. For illustrative purposes my invention will be shown and described as embodied in a machine of this character, although it is not thus limited in 25 scope but in its broader aspects, as will be evident, is applicable to various other constructions of the general type referred to.

My invention relates, more particularly, to the means for controlling the operation 40 of such machines, and the general object is to provide means whereby the operating mechanism may be actuated more readily and with the expenditure of less time and effort on the part of the operator than by prior constructions.

An important feature of the invention resides in the provision of a manually operative controlling member constructed preferably for rotary or turning movement about 45 an axis and arranged to actuate by such movement the mechanism for effecting an operation of the machine. As applied to the clicking machine this member will preferably serve also as the means whereby the operator moves the presser member into op-

erative position, and will be so arranged that as the operator grasps said member and swings the presser member thereby, movement of the controlling member relative to that of the presser member will follow by a natural and easy movement of the operator's hand, or may if desired be effected simultaneously with the swinging of the presser member so that the operation of the machine will take place at the instant when the presser member arrives at the desired operative position.

Other objects and features of the invention will appear from the following detailed description.

In the accompanying drawings, Figure 1 is a side elevation of a clicking machine with my invention embodied therein. Fig. 2 is a view, partly in vertical section, showing the structural details of the controlling member.

The frame 2 of the machine supports a cutting block or bed 4 and has bearings 6 and 8 for a vertically and rotatably movable post 10 to which is secured an arm or presser member 12. In the customary operation of the machine a sheet of stock, such as upper leather for use in the manufacture of boots or shoes, is placed upon the bed 4 and a suitable die arranged in the desired position thereon. The member 12 is normally up-raised above the plane of the bed a sufficient distance to clear the die, and may be swung to one side with the post 10 as a pivot so as to afford an unobstructed view of the bed. After the die is placed, the member 12 is swung to a position directly thereabove and mechanism is actuated which causes the post and the member 12 to descend and force the die through the stock and then to reascend to their former position. The bed 4 and the arm 12 thus constitute presser members that are relatively movable into and out of operative relation to each other and movable relatively also to operate upon the die. The operating mechanism for the post 10 may be of any desired construction, such for example as that disclosed in the patent to Bates previously referred to, and is not illustrated in detail. It includes, as shown, a clutch device 14, which preferably comprises a one-revolution non-repeating clutch and is arranged to be actuated through means that

includes a rod 16 connected to a lever 18 which is pivoted to the frame at 20 and provided with a ring member 22 loosely encir- 105

cling the post, the ring member having swiveled in a circumferential recess thereof a collar 24 to which is attached a rod 26 that extends forwardly over the presser member 12. The ring member, collar and rod thus constitute an extension of one end of the lever 18 so that by a depression of the forward end of the arm 26 the clutch may be actuated, while the collar 24 may turn about the pivotal axis of the post 10 and permit the arm 26 to move with the member 12 and assume any angular position of the latter without disturbing its operative relation to the lever 18. A spring 27 attached to the lever 18 tends to hold the rod 26 in raised position. These features are substantially such as are found in the commercial type of clicking machine and need no further description.

For imparting to the rod 26 its actuating movement I have provided a controlling member comprising in the preferred form shown an upright handle 28 formed with an annular depression 30 for receiving the forked end of the rod 26 and having a depending cylindrical sleeve 32. Fixed upon the forward end of the presser member 12 is a cylindrical member 34 which is arranged to be closely embraced by the sleeve 32. The cylinder 34 is formed with a cam groove 36, and the sleeve is provided with a screw 38 projecting inwardly therethrough and having a cylindrical end portion upon which is carried a roller 40 movable within the cam groove. The cylinder 34 is provided preferably with a central recess in which is seated a spring 42, the opposite end of which is arranged to bear upon the controlling member so as to maintain the latter at its limit of upward movement determined by the groove 36 in engagement with the roller 40. The spring 42, it will be noted, assists the action of the spring 27, and in case the latter is of sufficient strength the spring 42 may be dispensed with. The purpose of these springs is to maintain the parts of the actuating mechanism normally in inactive position, but they should be sufficiently light to permit actuating movement thereof when required with the least possible effort on the part of the operator. A rod 44 projects upwardly through the central part of the recess in the cylinder 34 and fits closely in a longitudinal recess 46 in the controlling member, thereby serving to keep the spring 42 in proper position and assisting in centering the controlling member with reference to the cylinder 34. Holes 48 serve to maintain atmospheric pressure in the space within the sleeve 32, and a hole 50 in the end of the handle performs a similar function for the recess 46.

The groove 36, the sides of which act as cam surfaces to guide the roller 40, is preferably formed with diametrically opposite

lower limits at the sides of the cylinder 34 from which portions of the groove curve upwardly and forwardly about the cylinder to a common meeting point disposed directly at the front with reference to the presser member 12. The groove thus presents two symmetrical portions extending downwardly from the common point toward the presser member and each curving about the cylinder through approximately ninety degrees of 75

With this construction it will be evident that any turning movement of the handle 28 about its upright axis in either direction from the normal inactive position shown in Fig. 2 will cause a corresponding proportional bodily downward movement thereof by virtue of the engagement of the roller 40 carried by the sleeve 32 with the cam surfaces of the cylinder 34 presented at the 85 sides of the groove 36.

The operation of the improved machine will be clear from the preceding description. With the presser member swung toward either side of the bed, the operator first places the die in the selected position upon the stock and then grasps the handle 28 and swings the presser member to a position above the die. By a slight turning movement of the hand, which follows easily and naturally the swinging movement of the arm in bringing the presser member to position, he may then effect the downward movement of the controlling member, which serves through the described connections to trip the clutch and cause an operation of the machine; after which the controlling member may be permitted to return automatically and quickly to its normal position. The direction of turning movement of the handle which will be most feasible or natural for the operator in any case will depend upon the first position of the presser member, at one side or the other of the location of the die, and the consequent direction of movement of the arm necessary to swing it to operative position. It is important to note, further, that in the hand of an experienced operator the movement of the controlling member may be rendered, in a sense, automatic as an incident of the operation of swinging the presser member into position. Such an operator, by grasping the handle and holding it firmly as he swings the presser member, may effect simultaneously 120 without conscious effort sufficient turning movement of the handle with respect to the presser member to finally trip the clutch at the instant when the presser member arrives at operative position above the die. For 125 varying ranges of movement of the presser member the operator may, with practice, easily acquire sufficient skill to correlate almost unconsciously the turning movement of his hand to the extent of swinging move- 130

ment of his arm so as to effect simultaneously such a turning movement of the handle as is necessary to trip the clutch at the proper point with reference to the movement of the presser member.

By the expression "operative position," as used herein with reference to the presser member is meant a position in which the presser member may be operated to impart pressure or deliver a blow at the required point, as for example upon a die placed in some selected position upon the stock, and the expression "inoperative position" signifies such a position of the member that the pressure or blow would not be delivered at the point required.

It should be understood that the cylinder 34 with its cam groove and the sleeve 32 with its engaging member are to be regarded broadly as relatively movable parts and that it is practically immaterial which of these members is arranged for bodily movement with the handle. Other variations also from the precise details of structure in the illustrated preferred embodiment of the invention are within the spirit and scope of the appended claims and will be obvious to those skilled in the art to which the invention relates.

Having described my invention what I claim and desire to secure by Letters Patent of the United States is the following:

1. In a machine of the class described, the combination with a presser member and mechanism for effecting automatically an operative movement thereof, of a manually operative controlling member connected with said mechanism and arranged for movement bodily in one direction to actuate the same and also for rotary movement, and means whereby a rotary movement of the controlling member serves to effect automatically said actuating movement thereof.

2. In a machine of the class described, the combination with a presser member and mechanism for effecting automatically an operative movement thereof, of a manually operative controlling member connected with said mechanism and arranged for bodily rectilinear movement to actuate the same and also for rotary movement, and means whereby a rotation of said member in either direction serves to effect automatically said actuating movement thereof.

3. In a machine of the class described, the combination with a presser member and mechanism for effecting automatically an operative movement thereof, of a manually operative controlling member connected with said mechanism and arranged for movement bodily in one direction to operate the same and also for limited rotary movement, means to retain the controlling member normally at a point intermediate the limits of its rotation, and means whereby a

rotation of said member in either direction from said point serves to effect automatically said actuating movement thereof.

4. In a machine of the class described, the combination with a presser member and mechanism for effecting automatically an operative movement thereof, of a manually operative controlling member connected with said mechanism and arranged for movement bodily in one direction to actuate the same and also for rotary movement, and means whereby a rotary movement of the controlling member serves to effect automatically said actuating movement thereof, said means comprising two relatively movable members one of which is carried by the controlling member, one of said members presenting a cam surface inclined to the direction of bodily movement of the controlling member and the other having means to engage said cam surface.

5. In a machine of the class described, the combination with a presser member and mechanism for effecting automatically an operative movement thereof, of a manually operative controlling member connected with said mechanism and arranged for movement bodily in one direction to actuate the same and also for rotary movement, and means whereby a rotation of said member in either direction serves to effect automatically said actuating movement thereof, said means comprising two relatively movable members one of which is carried by the controlling member, one of said members presenting a cam surface formed with two portions diverging from a common point and inclined to the direction of actuating movement of the controlling member, and the other member having means arranged to engage said surface normally at the point of divergence.

6. In a machine of the class described, the combination with a presser member and mechanism for effecting automatically an operative movement thereof, of a manually operative controlling member connected with said mechanism and arranged for movement bodily in one direction to actuate the same and also for rotary movement, and means whereby a rotary movement of the controlling member serves to effect automatically said actuating movement thereof, said means comprising a cylindrical member formed with a cam groove inclined to the direction of bodily movement of the controlling member, and a sleeve carried by the controlling member arranged to embrace said cylindrical member and movable with respect thereto, said sleeve having means arranged to travel in the cam groove.

7. In a machine of the class described, the combination with a presser member and mechanism for effecting automatically an operative movement thereof, of a manually

operative controlling member mounted upon the presser member and connected with said mechanism, said controlling-member being arranged for bodily movement with respect to the presser member to actuate said mechanism and also for rotary movement, and means whereby a rotary movement of the controlling member serves to effect automatically said actuating movement thereof.

8. In a machine of the class described, the combination with a stock supporting bed, a presser member and mechanism for effecting automatically an operative movement of the presser member with respect to the bed, of a manually operative controlling member mounted upon the presser member and connected with said mechanism, said controlling member being arranged for bodily movement with respect to the presser member to actuate said mechanism and for rotary movement in the path of said bodily movement, and means whereby a rotary movement of the controlling member in either direction serves to effect said actuating movement thereof.

9. In a machine of the class described, the combination of presser members arranged for relative bodily movement into and out of selected coöperative relation, means carried by and movable with one of said members whereby such movement may be effected, mechanism for effecting automatically a relative pressing movement of said members, and means whereby a turning movement of said first named means about an axis transverse to the first named path of movement of its carrying member serves to actuate said mechanism and cause the relative pressing movement of said members.

10. In a machine of the class described, the combination of a stock supporting bed, a presser member movable into and out of selected operative position with respect to said bed, means carried by the presser member whereby said movement may be effected, mechanism for effecting a relative pressing movement of the presser member and bed, and means whereby a turning movement of said first named means about an axis transverse to the first named path of movement of the presser member serves to actuate said mechanism and cause the relative pressing movement of said members.

11. In a machine of the class described, the combination of a bed, a presser member movable into and out of different operative positions with respect to said bed, a controlling member carried by the presser member whereby such movement may be manually effected, mechanism for effecting an operative movement of the presser member, said controlling member being movable in one direction with respect to the presser member to actuate said mechanism, said controlling member being arranged also for turning

movement with respect to the presser member, and means whereby the turning movement of the controlling member serves to effect automatically said actuating movement thereof.

12. In a machine of the class described, the combination of a bed, a presser member movable into and out of different operative positions with respect to the bed, a controlling member carried by the presser member whereby such movement may be manually effected, mechanism for effecting an operative movement of the presser member with respect to the bed, said controlling member being arranged for independent movement toward and from the presser member and for turning movement about an axis in line with the direction of its movement toward the presser member, means whereby the movement of the controlling member toward the presser member serves to actuate said mechanism and cause an operative movement of the presser member with respect to the bed, and means whereby the turning movement of the controlling member serves to effect automatically said actuating movement thereof.

13. In a machine of the class described, the combination of a bed, a presser member movable to a selected operative position with respect to the bed from a position at one side of said selected position, a controlling member carried by the presser member whereby such movement may be manually effected, mechanism for effecting an operative movement of the presser member toward the bed, said controlling member being movable in either direction about an axis transverse to the first named path of movement of the presser member, and means whereby a movement of the controlling member in either direction about said axis serves to actuate said mechanism for effecting an operative movement of the presser member.

14. In a machine of the class described, the combination of a bed, a presser member movable from a position at one side of a die on the bed to an operative position with respect to the die, a controlling member carried by the presser member whereby such movement may be manually effected, mechanism for effecting an operative movement of the presser member toward the bed, said controlling member being movable in one direction with respect to said presser member to actuate said mechanism, said controlling member being arranged also for turning movement in either direction from a normal intermediate position about an axis transverse to the first named path of movement of the presser member, and means whereby the turning movement of the controlling member serves to effect automatically said actuating movement thereof.

15. In a machine of the class described, the combination of a bed, a presser member mounted to swing from an inoperative to an operative position with respect to a die on the bed, a manually operative controlling member arranged to swing with the presser member whereby such movement of the latter may be effected, said controlling member being arranged for rotary movement with respect to the presser member, mechanism for effecting automatically an operative movement of the presser member with respect to the bed, and means whereby the rotary movement of the controlling members 5 serves to actuate said mechanism.
16. In a machine of the class described, the combination of a bed, a presser member pivoted to swing from an inoperative to an operative position with respect to a die on the bed, a controlling member carried by the presser member whereby such movement may be manually effected, mechanism for effecting an operative movement of the presser member toward the bed, said controlling member being arranged for turning movement about an axis transverse to the first named path of movement of the presser member and for movement automatically toward and from the presser member in proportion to the extent of such turning movement, means to keep the controlling member normally at the limit of its movement in a direction away from the presser member, and means whereby a movement of the controlling member toward the presser member 20 serves to actuate said mechanism for effecting an operative movement of the presser member toward the bed.
17. In a machine of the class described, the combination of a bed, a presser member movable to different operative positions with respect to the bed, a handle carried by the presser member whereby such movement may be effected, mechanism for effecting an operative movement of the presser member toward the bed, said handle being movable toward and from the presser member, connections whereby the handle serves to actuate said mechanism on its movement toward the presser member, said handle being movable also with respect to the presser member about an axis parallel to its path of movement toward said member, and means whereby the turning movement of the handle 25 about its axis serves to effect automatically said actuating movement thereof, said means including two members, one fixed with respect to the presser member and the other movable with the handle, one of said members presenting a cam surface inclined to the direction of actuating movement of the handle and curved about the axis of rotary movement of said handle, and the other member having means to engage said cam surface.
18. In a machine of the class described, the combination of a bed, a presser member movable to a selected operative position with respect to the bed from a position at one side of said selected position, a controlling member carried by the presser member whereby such movement may be manually effected, said controlling member being arranged for rotary movement with respect to the presser member, mechanism for effecting an operative movement of the presser member with respect to the bed, and means whereby a rotary movement of the controlling member of substantially ninety degrees 30 serves to actuate said mechanism.
19. In a machine of the class described, the combination of a bed, a presser member movable from a position at one side of a die on the bed to an operative position with respect to the die, a controlling member carried by the presser member whereby such movement may be manually effected, said controlling member being arranged for rotary movement with respect to the presser member, mechanism for effecting an operative movement of the presser member with respect to the bed, means for retaining the controlling member normally in a predetermined angular position, and means whereby a rotary movement of said member of substantially ninety degrees in either direction 35 from said normal position serves to actuate said mechanism for effecting an operative movement of the presser member.
20. In a machine of the class described, the combination of a bed, a presser member mounted to swing about an upright axis from a position at one side of a die on the bed to an operative position with respect to the die, a manually operative controlling member arranged to swing with the presser member whereby such movement of the latter may be effected, mechanism for effecting automatically an operative movement of the presser member with respect to the bed, said controlling member being connected with said mechanism and arranged for movement bodily with respect to the presser member for actuating said mechanism, said controlling member being arranged also for 40 rotary movement, and means whereby a rotary movement of the controlling member of approximately ninety degrees serves to effect said actuating movement thereof so as to cause the operation of the presser member.
21. In a machine of the class described, the combination of a bed, a presser member mounted to swing from a position at one side of a die on the bed to an operative position with respect to the die, a manually operative controlling member arranged to swing with the presser member whereby such movement of the latter may be effected, mechanism for effecting automatically an operative move- 45

6
ment of the presser member with respect to the bed, said controlling member being connected with said mechanism and arranged for movement bodily in one direction with respect to the presser member for actuating said mechanism, said controlling member being arranged also for rotary movement, and means whereby a rotary movement of the controlling member of approximately 10 ninety degrees in either direction from its normal position serves to effect said actuating movement thereof so as to cause the operation of the presser member.

22. In a machine of the class described, 15 the combination with a bed, of a presser member movable over the bed from inoperative to operative position, mechanism for effecting an operative movement of the presser member toward the bed, and means 20 for actuating said mechanism comprising a member movable with the presser member and arranged to be grasped by the hand of the operator, said member being movable relatively to the presser member in such manner 25 that as the presser member moves into operative position the relative movement of the hand of the operator and the presser member incident to such movement of the presser member will serve to effect the necessary

movement of said actuating member to 30 cause an operation of the machine.

23. In a machine of the class described, the combination with a bed, of a presser member movable over the bed from inoperative to operative position, mechanism for 35 effecting an operative movement of the presser member toward the bed, and means for actuating said mechanism comprising a member carried by the presser member and arranged to be grasped by the hand of the 40 operator for moving the presser member into operative position, said member being movable relatively to the presser member in such manner that as the presser member is moved into operative position the relative 45 movement of the hand of the operator and the presser member incident to said movement of the presser member will serve to effect the necessary movement of said actuating member to cause an operation of the 50 machine.

In testimony whereof I have signed my name to this specification in the presence of two subscribing witnesses.
